GAS MAIN STOPPER

George A. Behringer, Brooklyn, N. Y.

Application March 3, 1939, Serial No. 259,603

6 Claims. (Cl. 138—94)

This invention relates to gas main stoppers in general, and more especially to the type including a pair of collapsible jaws.

Among the objects of the present invention, it is aimed to provide an improved gas main stopper having a pair of collapsible jaws associated with one-piece yieldable closure forming disc or diaphragm. The diaphragm has a yieldable sealing rim associated therewith intimately to engage the inner periphery of the main effectively to stop the passage of gas therethrough.

It is still another object of the present invention to provide an improved gas main stopper having a pair of collapsible jaws associated with a rubber disc having a yieldable rim. The disc is yieldable to enable insertion of the disc supporting jaw members and disc through a small opening in the main to be shut off when the jaw elements are collapsed and the disc is folded; and the rim is conformable to the inner periphery of the main when the jaws are opened and the disc is folded and erected transversely across the main to be shut off.

It is still another object of the present invention to provide an improved gas main stopper having a pair of collapsible jaws associated with a rubber disc having a pneumatic inflatable rim associated therewith to conform itself to the inner periphery of the main to be shut off when the jaws are opened, the disc unfolded and erected transversely across the main, and the rim is intimately to engage the inner periphery of the main effectively to stop the passage of gas therethrough.

These and other features, capabilities, and advantages of the invention, will appear from the subjoined detailed description of specific embodiments thereof illustrated in the accompanying drawing in which:

Figure 1 is a side elevation, partly in section, of the gas main stopper as it is initially inserted to a main, according to one embodiment thereof;

Fig. 2 is an enlarged section of the embodiment illustrated in Fig. 1, with the jaws opened, the disc erected, and the rim inflated;

Fig. 3 is a section on the line 3—3 of Fig. 1;

Fig. 4 is a reduced section on the line 4—4 of Fig. 2;

Fig. 5 is a section on the line 5—5 of Fig. 1;

Fig. 6 is an enlarged fragmental section showing the connection of a disc with the jaw members of the embodiment illustrated in Figs. 1 to 5 inclusive; and

Fig. 7 is an enlarged fragmental section showing

the connection between the disc and the jaw of another embodiment.

In the embodiment shown in Figs. 1 to 6 inclusive, the main 1 to be repaired may be of different sizes generally having an inside diameter of 3", 4", 6", 8", 10" or 12", and preferably not over 16", and a wall thickness of approximately $\frac{3}{8}$ " to $\frac{5}{8}$ ", depending upon the pressure for which the main is to be used.

In the illustration of Figs. 1 and 2, it is assumed that the gas is moving in the direction of the arrow 2. In practice, when a portion of the main 1 is to be repaired, either to stop a leak or to be connected or disconnected from a certain installation, a portion of the main 1 is tapped at a point removed from the leak or point of repair or construction. The size of the opening so tapped, with a main having an inside diameter of not less than 3", does not exceed $1\frac{1}{4}$ " in diameter when a gas main stopper such as the present is intended to be used.

The gas main stopper of the embodiment illustrated in Figs. 1 to 6 inclusive, see Fig. 4, consists essentially of two complementary jaws 3 and 4. Each of these jaws 3 and 4 consists essentially of a shank 5 rectangular in cross section, having an outwardly extending grip or handle 6 at one end and an arcuate formation 7 at the other end extending in the same direction as the handle. The handles 6 of the jaws 3 and 4 extend away from one another when the jaws are opened, as shown in Fig. 4, and the arcuate formations 7 similarly extend away from one another to complement one another in the formation of a circular frame. The lower ends of the arcuate formations 7 are pivotally connected to the cross piece 8 spacing the lower ends from one another when the jaws are collapsed, as shown in Fig. 1.

Intermediate the shank 5 and the arcuate formation 7 of each jaw, there is, see Figs. 2 and 3, provided an outwardly extending curved clearance portion 9. These clearance portions 9, see Fig. 3, extend outwardly from one another when the jaws are in collapsed position, that shown in Figs. 1 and 3. In opened position of the jaws, these clearance portions 9, see Fig. 2, extend away from the gas supply indicated by the arrow 2 and toward the point of repair or construction.

Mounted on the shanks 5 of the jaws 3 and 4 is a positioning frame 10 having a plate 11 engaging the shanks 5, with a lower lip 12 to rest on the outer periphery of the main 1, as shown in Fig. 1, and a curved tongue 13 having a tapered end 14 notched at 15, to engage

the wall of the main 1, as shown in Fig. 2. For anchoring the positioning member 11 in position on the shanks 5 when the jaws are opened into the position shown in Fig. 2, and at the same time anchoring the jaws in their open position, there is provided the U-shaped plate 16, see Fig. 5, through which extends the bolt 17, which bolt is preferably connected to the plate 11 in the present instance shown as having a head 18 connected to the plate 11. The free threaded end of the bolt 17 has a wing nut 19 screw-threadedly mounted thereon, to engage the washer 20 between which washer 20 and the intermediate web of the U-shaped plate 16 there is positioned a coil spring 21 surrounding the bolt 17. Preferably, as shown, the spring 21 is disposed in a cylindrical thimble 22, one end of which is adapted to rest against the intermediate web of the U-shaped plate 16, and the other end of which is adapted to engage the washer 20 when the wing nut 19 is turned into its final locking position.

As the wing nut 19 is gradually released, it will, due to the spring 21, yieldably maintain jaws 3 and 4 in position until force is applied to fold them together into their collapsed position, that shown in Fig. 3, when, due to the angular formation of the shanks 5, the U-shaped plate 16 and plate 11 will again yieldably anchor the jaws 3 and 4 in their collapsed position. However, when the wing nut is turned to permit movement of the jaws 3 and 4 into and out of open position, the locking pressure of the spring 21 will have been sufficiently diminished to permit the plates 11 and 16 to be slid upwardly out of engagement with the main 1 and permit the stopper again to be removed from the main.

The main feature of the invention now to be described, consists in providing for the arcuate formations 7, the yieldable disc consisting in the embodiment shown in Fig. 6, of a rubber disc member 23 having a pneumatic inflatable rim 24, a clincher flange 25, and a supply tube 26. In the embodiment shown in Fig. 6, the clincher flange 25 is initially inserted between the crescent shaped opposing flanges 27 and 28 of the arcuate formations 7, and then these opposing flanges 27 and 28 pressed together to anchor the clincher flange 25 of the disc 23. Preferably, as shown, the supply tube 26 will be positioned so that it extends upwardly between the upper ends of the clearance members 9 of the jaws 3 and 4.

With this embodiment, it will thus appear that after the opening has been tapped in the main 1, and the jaws 3 and 4 are collapsed, the rubber disc 23 and rim 24 will yield to permit the arcuate formations 7 to be inserted through the tapped opening into the interior of the main 1, thereupon the jaws opened into the position shown in Fig. 4, thereupon the device erected so that the disc 23 and rim 24 will extend transversely across the main 1, thereupon the positioning device 10 brought down into engagement with the wall of the main 1, as shown in Fig. 2, and the wing nut 19 turned to anchor the positioning device 10 in this position, and at the same time anchoring the jaws 3 and 4 in their opened position, and thereupon air supplied through the tube 26 to inflate the rim 24 until it intimately engages the inner face of the main 1 and effectively shuts off any passage of gas through the main 1 at this area.

In some instances, especially with the gas main stoppers adapted for the smaller sizes, and where lower pressures are used, the rim 29 of the disc 30, see the embodiment shown in Fig. 7, may

be composed of solid rubber. In this embodiment, the locking flange 31 is formed on the rim 29 between which and the disc a single flange 32 of an arcuate formation 7 will extend and rivet 33 provided which connect the disc 30 and flange 31 of the rubber element to the flange 32 of the metal arc formation 7.

It is, of course, obvious that the various parts associated with the jaws 3 and 4 are preferably composed of metal, and that the disc 23 with its associated rim 24, clincher flange 25, and tube 26, are composed of rubber or the like yieldable material, and similarly that the disc 30 and its associated rim 29 and clincher 31 are composed of rubber, rubberized canvas or the like yieldable material.

When the jaws are equipped, according to the embodiment illustrated in Fig. 7, obviously the outer periphery of the rim 29 in open position should normally exceed the cross sectional inner area of the main 1, and reliance placed upon the compressibility of the rim 29 intimately to engage the inner face of the main 1. Furthermore when the jaws are equipped, according to the embodiment shown in Fig. 7, ordinarily when positioning the stopper in a main 1, it will be inclined to the cross section of the main, thereupon the jaws will first be opened, then the shanks 5 engaged and pressed with the wall of the main 1 at a fulcrum until the disc 30 is erected at right angles to the axis of the main 1 when the compressible rim 29 will be forced into intimate engagement with the inner face of the main.

It is obvious that various changes and modifications may be made to the details of construction without departing from the general spirit of the invention set forth in the appended claims.

I claim:

1. A gas main stopper comprising a pair of tongs, each tong having an arcuate formation, a handle, and a shank angular in cross section intermediate said arcuate formation and said handle, a cross piece movably connecting adjacent ends of said arcuate formations, the arcuate formation and the handle of each tong extending in the same direction to enable arcuate formations and handles to be parallel and extending in the same direction in the closed position of the tongs, and in alignment with one another in open position of the tongs, a flange for formations on said arcuate formations, a one-piece yieldable disc having a rim connected to said flange formations, and a frame having separable plates engaging opposite sides of said shank, a threaded stem extending from one plate through the other, a wing nut screw-threadedly mounted on said stem, and a coil spring intermediate said wing nut and the plate through which said stem extends yieldably resisting the tightening of said nut to clamp said plates against said shanks.

2. A gas main stopper comprising a pair of tongs, each tong having an arcuate formation, a handle, and a shank angular in cross section intermediate said arcuate formation and said handle, a cross piece movably connecting adjacent ends of said arcuate formations, a one-piece yieldable disc connected to said arcuate formations, a frame having separable plates engaging opposite sides of said shanks, a threaded stem extending from one plate through the other, a wing nut screw-threadedly mounted on said stem, a coil spring intermediate said wing nut and the plate through which said stem extends yieldably resisting the tightening of said nut to clamp said plates against said shanks.

clamp said plates against said shanks, a cylindrical thimble enclosing said spring and engaging the plate through which said stem extends, and a washer disposed between said thimble and said wing nut.

3. A gas main stopper comprising a pair of tongs, each tong having an arcuate formation, a handle, and a shank angular in cross section, intermediate said arcuate formation and said handle, a cross piece movably connecting adjacent ends of said arcuate formations, the arcuate formation and the handle of each tong extending in the same direction to enable arcuate formations and handles to be parallel and extending in the same direction in the closed position of the tongs, and in alignment with one another in open position of the tongs, flange formations on said arcuate formations, a one-piece yieldable disc having a rim connected to said flange formations, a frame having separable plates engaging opposite sides of said shanks, means connecting said plates to one another, and a lip and a curved tapered finger on one of said plates, the lip engaging the outer face of the main to be repaired and the finger extending through the opening formed in the main to be repaired and having a recess to engage the wall of the main to be repaired.

4. A gas main stopper comprising a pair of metal tongs, each tong having an arcuate formation supplementing one another to form a ring in open position, a metal flange formation extending outwardly from each arcuate formation, a cross piece pivotally connected at its ends to adjacent ends of said arcuate formations, shanks extending from the other ends of said arcuate formations, means operatively associated with said shanks and operable to anchor said arcuate formations in open position with the arcuate formations in alignment with said cross piece and extending away from one another, and a one piece rubber element comprising a rubber disc having integral therewith an enlarged rubber rim and a rubber flange integral with said rubber rim extending inwardly and parallel to said rubber disc, said rubber flange connected to said metal flange formations to anchor said rubber flange against accidental displacement and to facilitate folding said rubber disc over upon itself when removing said stopper from,

or inserting said stopper into, operative position in a gas main.

5. A gas main stopper comprising a pair of metal tongs, each tong having an arcuate formation supplementing one another to form a ring in open position, a metal flange formation extending outwardly from each arcuate formation, a cross piece pivotally connected at its ends to adjacent ends of said arcuate formations, shanks extending from the other ends of said arcuate formations, means operatively associated with said shanks and operable to anchor said arcuate formations in open position with the arcuate formations in alignment with said cross piece and extending away from one another, a one piece rubber element comprising a rubber disc having integral therewith an enlarged solid rubber rim and a rubber flange integral with said rubber rim extending inwardly and parallel to said rubber disc, and means connecting said rubber flange to said metal flange formations to facilitate folding said rubber disc over upon itself when removing said stopper from, and inserting said stopper into, operative position in a gas main.

6. A gas main stopper comprising a pair of metal tongs, each tong having an arcuate formation supplementing one another to form a ring in open position, a pair of metal flange formations extending outwardly from each arcuate formation, a cross piece pivotally connected at its ends to adjacent ends of said arcuate formations, shanks extending from the other ends of said arcuate formations, means operatively associated with said shanks and operable to anchor said arcuate formations in open position with the arcuate formations in alignment with said cross piece and extending away from one another, and a one piece rubber element comprising a rubber disc having integral therewith an enlarged in-

flatable rubber rim and a rubber flange integral with said rubber rim extending inwardly and parallel to said rubber disc, said pairs of metal flange formations receiving said rubber flange and compressed to anchor said rubber flange against accidental displacement and to facilitate folding said rubber disc over upon itself when removing said stopper from, or inserting said stopper into, operative position in a gas main.

GEORGE A. BEHRINGER. 50
